UNITED STATES PATENT OFFICE.

GEORGE E. BATES AND ROBERT DEY, OF SYRACUSE, NEW YORK.

DESIGN FOR A SEAT FOR SADDLES.

SPECIFICATION forming part of Design No. 25,153, dated February 11, 1896.

Application filed December 16, 1895. Serial No. 572,368. Term of patent 7 years.

To all whom it may concern:

Be it known that we, GEORGE E. BATES and ROBERT DEY, citizens of the United States, residing at Syracuse, in the county of Onondaga and State of New York, have invented and produced a new and original Design for Seats for Saddles for Cycles, of which the following is a specification, reference being had to the accompanying drawings, in which we show, in—

Figure 1, a top plan of the seat portion of the saddle, and Fig. 2 a transverse section thereof.

The leading features of our design consist in the rear portion being upon the arc of a circle, the ends of the arc being rounded inwardly and connected by concaved lines to the edges of the stem and thence extending by partly-straight and partly-convex lines to the head of the pommel, the center lines of said stem longitudinally being upon a line radial to the arc of the circle of the rear portion.

A is the saddle-seat, having its rear edge *a* upon the arc of a circle, having the extremi-

ties of said are connected by a convex edge *b* to the starting-point of a concave edge *c*, which by arcs of varying radii create the front edges and merge into the partly-straight and partly-convex edges *d* of the stem or pommel ³⁰ *e* and at the front end thereof meeting by convex corners merging into a straight line, the longitudinal center line of this stem being radial to the arc of the circle of said rear edge and bisecting it if extended thereto. Between ³⁵ such radial line and the extremities of the are of the rear edge the surface of the body of the seat is more or less concave, as at *h*. The edges of said seat are more or less rounded, substantially as indicated by the shading. ⁴⁰

What we claim is—

The design for a seat for a saddle for cycles substantially as shown and described.

In witness whereof we have hereunto set our hands on this 30th day of November, 1895.

GEORGE E. BATES.
ROBERT DEY.

In presence of—

JESSIE E. MURRAY,
HOWARD P. DENISON.
